CLAIM

The ornamental design for a dental floss dispenser and applicator, as shown and described.

DESCRIPTION

FIG. 1 is a top perspective view of a dental floss dispenser and applicator showing our new design;

FIG. 2 is an end view thereof;

FIG. 3 is a top elevational view thereof;

FIG. 4 is a second end view thereof;

FIG. 5 is a right side view thereof;

FIG. 6 is a left side view thereof; and,

FIG. 7 is a bottom elevational view thereof.

Elements shown in dotted are environmental only, and form no part of the claimed design.
